GASIFYING APPARATUS FOR HEAVY FUELS

Esteban Colla and Umberto Cassina, Buenos Aires, Argentina

Application March 18, 1935, Serial No. 11,746

4 Claims. (123—133)

The present invention relates to improvements in gasifying apparatuses for gas-oil and similar heavy fuels, applicable to explosion motors in general, its chief object consisting in certain useful constructional and operating improvements in this class of apparatuses, these improvements permitting both a considerable increase in the output of these devices and the attainment of other evident practical and economical advantages which still further increase the efficiency of the aforementioned apparatuses.

The invention has still further objects in mind which will be disclosed as the present specification proceeds and more particularly be determined in the appended claims.

In order that the invention may be clearly understood and readily put into practice it has been shown by way of example in the accompanying drawings wherein:

20 Figure 1 is a front view of the apparatus,
Figure 2 is a plan view of the same,
Figure 3 is a horizontal section along line 3—3 of Fig. 1,
Figure 4 is a transversal section along line 4—4 of Fig. 1, and
25 Figures 5, 6 and 7 are vertical sections, respectively, along lines 5—5, 6—6 and 7—7 of Fig. 2.
In all the figures, the same reference letters and/or numerals indicate corresponding parts.

30 In the form of construction as illustrated, the apparatus in accordance with the invention comprises essentially two principal bodies A and B suitably joined together and combined one with another in the manner as will be pointed out hereinafter.

35 The body A chiefly comprises the chamber 1, preferably of an elongated shape, wherein the heating of the heavy fuel takes place, the said fuel entering through a lower aperture 2 whereto a pipe is connected which communicates with the fuel tank X. The front wall of the said chamber carries a cover 3 bolted or otherwise fastened to it and provided with an orifice 4 connected with a carburettor Y at the entrance of which a cloth 40 or a wire gauze 5 is disposed in order that it may act as a filter for the heavy fuel issuing from the chamber 1. The hot fuel passes to the carburettor through a conduit suitably connected to the orifice 4 of the cover 3.

50 The chamber or container 1 is partially or completely surrounded by a second amply proportioned chamber 6 for the circulation of the exhaust gases, the lateral pipes 7 extending therefrom and with the flanges 9 fixed to their inlets 8, both the position and the shape of the said inlets

and flanges 9 register, respectively, with the corresponding inlets 10 and 11 provided on the rear body B of the apparatus.

Both, chamber 1 and chamber 6 for the circulation of the exhaust gases are rearwardly limited by a common plate 12 which acts, at the same time as a partition or diaphragm between the units A and B of the apparatus. The said plate is provided at the top with an aperture 13 in connection with a chamber 14 formed in the rear structure and from which the pipe 15 extends, the exhaust gases being expelled through this pipe upon having travelled through the inside of the apparatus.

The rear structure B of the apparatus which, as has been stated, is directly attached to the structure A, is fastened to the latter by a series of bolts 16 or similar means which are thrust through a flange in the front portion of the apparatus, and by bolts which connect the flanges 9 and 11.

The rear structure B comprises a gasification chamber 17 having an elongated form, and is provided with an intake 18 in its lower portion whereto the fuel carburettor is connected. Inside 25 of this chamber a series of vanes or blades 19 is disposed which, as will be noted, form together a series of passages with opposed inclinations extending from the center, these passages being alternately interconnected at their medial line and their ends. Thus, the fuel to be gasified, upon leaving the carburettor, is forced to flow in zig-zag, as is indicated by the arrows of Fig. 5.

The lateral conduits 20 extend from the said chamber 17 and are interconnected with the inlet ports of the motor cylinders through the end inlets 21.

At the back of the described unit, i. e., behind the gasification chamber 17, another, third chamber 22 is arranged for the circulation of the exhaust gases as they enter into the apparatus. These gases pass into this chamber through the inlet 23 which communicates with the central motor exhaust conduit, and leave the same through the outlets 10 which, as has been said before, interconnect with the end inlets 8 of the tubes 7 forming an integral part of the front structure A. When the flanges 9 of the structure A join the flanges 11 of the structure B, the inlets 8 and 10 follow one upon the other so that the exhaust gases entering through the inlets 23 of the rear chamber 22 may freely pass through the conduits 7, the chamber 6 and, after having passed through the aperture 13 and the upper 50

chamber 14, may flow out into the air through the pipe 15.

Inside of the chamber 22 the partitions 24 are arranged which will cause the exhaust gases to move towards the upper portion of the apparatus at which point the enlargement 25 is located. The said partitions have for their object to cause the gases to pass through as long a path of travel as is possible before they leave the chamber 22, this path of travel being clearly indicated by the arrows of Fig. 6.

As may be seen also from the aforementioned figure, the rear chamber 22 is separated from the exhaust chamber 14 by means of a suitably arranged partition 26. In the aperture 27 of this partition, which connects the chamber 22 to the chamber 14, a wing-valve 28 is provided, the same being mounted on a shaft 29 projecting from the apparatus and equipped with an arm 30 by means of which the wing-valve may be given all kinds of inclinations, that is to say, from the position at which it would close the aperture 27, to that at which it would completely open the passage through the said apparatus. This contrivance allows of regulating the heat transmitted to the gasification chamber 17 by means of a larger or smaller stream of exhaust gases which may circulate about the same, determined by the smaller or larger amount of such gases caused to directly pass towards the outlet 14.

As a consequence of the manner in which the unit of the apparatus is arranged, the gasification chamber 17 is subjected to direct heating by the exhaust gases which circulate through the chambers 6 and 22 from which it is separated by the partition 12 as described before, and by the rear partition 31 which separates chamber 17 from chamber 22, while this same heating acts also on one of the walls of the conduits 20 through which the gasified fuel flows out.

With a view to complete the aforescribed apparatus, a small pipe 32 extends from the gasification chamber 17 which, after passing through the rear and front walls of the chamber 6, issues from the end of the apparatus, while this pipe, at the same time, facilitates the free entrance of the necessary amount of air into the said gasification chamber. Furthermore, a small open pipe 33 is provided which communicates with the inside of the chamber or container 1 so as to allow of the free escape of any compressed gases that might form in the inside of the same as a consequence of the heating of the fuel.

The operation of this apparatus is extremely simple and will now be described in detail.

The operation of the motor will be initiated, preferably with gasoline sent directly to the carburetor from a convenient tank.

A portion of the motor exhaust gases enters into the apparatus through the inlets 23 and, after travelling through the chamber 22, then passes through the inlets 10, 8, the conduits 7, the chamber 6, the aperture 13 and the chamber 14, finally making its exit through the pipe 15. During this travel, the exhaust gases will produce a potent heating in the chambers 1 and 17 as well as in the conduits 20 from which they are separated by thin partitions. A moment will then arise at which the high temperature created by the gases will be sufficient to bring about the gasification of the heavy fuel, be it gas-oil or of another nature, whereupon the operation of the motor will be started with this fuel.

The heavy fuel present in the chamber 1 and 75 which will have been previously heated due to the

action of the exhaust gases surrounding the said chamber, after filtering through the wire gauze 5 will pass to the carburetor from which it will pass into the gasification chamber 17 through the lower portion. Due to the suction effect of the 5 motor cylinders, the vaporized fuel will pass through the inside of the said chamber 17 in the sense as is indicated by the arrows, at the same time undergoing a complete gasification by virtue of the high temperature imparted to it by the 10 exhaust gases which circulate through the adjacent chambers 6 and 22. The fuel so gasified and mixed with the suitable amount of air which enters through the pipe 32, will pass to the conduits 20 and finally flow out through the outlets 15 21 in order to flow to the cylinder inlet conduit.

The other portion of the gases issuing from the other two exhaust outlets will directly pass through two rear outlets 34 arranged as an extension of the outlets 10, in the passages 8 these 20 gases will mix with those that came from the chamber 22 whereupon they will travel together through the conduits 7, the chamber 6, the passages 13 and 14, and flow out through the pipe 15.

It is obvious that various constructional and detail modifications may be introduced without thereby departing from the scope of the present invention which is clearly ascertained in the appended claims.

What we claim is:

1. A gasifying apparatus for gas-oil and similar heavy fuels, applicable to explosion motors in general, which comprises a front unit having a fuel chamber for the heavy fuel, said chamber being provided with a fuel supply inlet and a fuel outlet for communicating with a carburetor and a heating chamber extending about the fuel chamber and having lateral branch conduits for the entrance of the motor exhaust gases for heating the fuel chamber, said heating chamber 40 being enlarged at its upper portion and having at that point an outlet for the exhaust gases, a rear unit adjacent to the front unit having formed therein a gasification chamber provided with baffles so arranged that a zig-zag travel is 45 imparted to the vaporized fuel entering through the lower portion of the said chamber, said gasification chamber having lateral conduits for communicating with the intake ports of the motor, said second unit having a central chamber arranged at its rear portion and provided with a port for communicating with the central exhaust ports of the motor, this central chamber having lateral conduits communicating with the lateral conduits of the front unit and with the end exhaust ports of the motor, the second unit being so constructed that the gasification chamber lies 50 between walls of the said central chamber of the second unit and the fuel heating chamber of the first unit through which the exhaust gases 60 circulate.

2. A gasifying apparatus, as defined in claim 1, wherein the rear central chamber for the circulation of the exhaust gases is provided at its top with a chamber separated from it by a partition, said separate chamber communicating with the exhaust outlet of the heating chamber of the front unit and in turn having an exhaust outlet, said partition being provided with a port 65 having therein a wing valve operable to regulate the passage thereto of exhaust gases from the central chamber.

3. A gasifying apparatus for combustion motors of the class described, comprising a body having a fuel receiving chamber, a heating cham- 75

- ber extending about the fuel chamber and a gasification chamber into which the fuel is fed, a passage for the exhaust gases of the motor in said body extending to the heating chamber for leading the exhaust gases of the motor about the same to heat the fuel therein and to heat a wall of the gasification chamber, a second passage for exhaust gases of the motor for leading said exhaust gases into contact with another wall 5 of the gasification chamber and into the heating chamber, said fuel and gasification chambers having fuel inlet ports adapted to communicate with the carburetor and a common exhaust outlet for the exhaust gases.
- 15 4. A gasifying apparatus for combustion motors of the class described, comprising a body having a fuel receiving chamber, a heating chamber extending about the fuel chamber and

a gasification chamber into which the fuel is fed, a passage for the exhaust gases of the motor in said body extending to the heating chamber for leading the exhaust gases of the motor about the same to heat the fuel therein and to heat a wall 5 of the gasification chamber, a second passage for exhaust gases of the motor for leading said exhaust gases into contact with another wall of the gasification chamber and into the heating chamber, said fuel and gasification chambers having 10 fuel inlet ports adapted to communicate with the carburetor, a common exhaust outlet for the exhaust gases and means for shunting exhaust gases from the second passage direct to the exhaust outlet.
